SHAPER FEED MECHANISM

Application filed March 5, 1926. Serial No. 92,561.

This invention is devoted to the organization of shaping-machines with special relation to the means for feeding the work. As the work on the table may be narrow or wide and, as the portion to be machined may be near to or far from the main frame, it is customary to provide the ram with corresponding adjustments, i. e. (1) to vary its overhang, (2) to vary its length of stroke and (3) to vary its frequency of stroke. 5 It is likewise desirable to be able to adjust the length of the feed-stroke of the table so that the tool may take heavier or lighter cuts according to the material and the finish, and it is desirable that the direction of feed may be reversible. It is also necessary that the advances of the work-table shall be made while the tool is out of the work and, to attain the utmost smoothness 10 of action, it is desirable that the feed-stroke shall start not too long after the tool leaves the work and be completed just before the tool again engages the work; this being especially desirable when the strokes of the 15 ram are short in length but rapid in frequency and before leave only very short non-cutting periods for accomplishing the advance of the table.

The regulation of the length of the feed-stroke should be possible without disturbing the timing of the feed with the ram, and to enable the user to attain the maximum feed safe for the work in hand, he should be able to make the regulation while 20 the machine is running and the hand-grasp should at all times be free from movement or oscillation. And for structural reasons, the mechanism for converting the continuous motion into the intermittent feed motion (as well as its regulating means) should be simple, compact, quiet and in the nature of a self-contained unit. These are 25 within the objectives of this invention.

To keep the pawl always in contact with 30 the ratchet wheel, and to avoid starting its advance when not already in tooth-engagement, is also an aim of the invention; the regulation of the length of the feed-stroke being now accomplished, not by swinging the 35 pawl through a fixed length of arc and

lifting it out of engagement during an adjustable portion of its swing, but by regulating the length of its arc of swing yet always keeping it against the ratchet wheel. In the present form, a stationary or inert 40 stop is shiftable into different fixed positions and it thereby limits the return-stroke of the pawl and thus regulates the extent of the lost-motion between the pawl and an actuator which periodically oscillates 45 through a fixed arc. When the actuator retreats, it is quietly and smoothly followed by the pawl to the extent permitted by the station to which the inert stop has been adjusted; whereupon the actuator continues 50 its retreat unaccompanied and there is no noisy "snap-back" of the pawl. When the actuator advances, it goes alone until the adjustable lost-motion has been taken up, and it then pushes the pawl forward to the end 55 of the advanced stroke. The limit of the advance stroke of the pawl always occupies an invariable position, but the limit of the return of the pawl occupies whatever position has been selected by the adjustment. 60 This principle, involving an inert stop (adjustable into various positions) cooperating with an actuator to hold a pawl-shifting spring always under restraint, is the basis 65 of one of the objects of the present invention; the spring being never able suddenly to shift the pawl but restrained to move it no faster than the travel of the actuator. Thus is avoided the objectionable "snap-back" and the action is correspondingly 70 quieted.

In point of general organization, this invention aims to locate at the cross-rail (*a*) a converter for deriving oscillatory motion from continuous motion (*b*) a stationary 75 regulator for determining the amplitude of oscillation and (*c*) a stationary directional control. Also, it aims, through the agency of a single uni-directional shaft (extending from the main-frame to the cross-rail) which 80 rotates once for each tool stroke, to convey the motion to the converter.

In a feeding mechanism constructed in accordance with my invention a swivel and 85 spline shaft has one end thereof connected 90

to the crank gear mechanism and has the other end thereof supported on the cross-rail. The continuously rotating universal shaft operates a crank mechanism on the cross-rail in accordance with the reciprocating movement of the ram. The crank mechanism in turn oscillates a lever through a fixed arc. The oscillating lever is mounted on a feed shaft adjacent to a pawl lever and a stop member. The pawl lever has a portion thereof extending into the path of movement of a projection from the oscillating lever so as to be moved by the oscillating lever. A spring member is provided for exerting a force tending to hold the pawl lever in engagement with the projection from the oscillating lever. The stop member, which is adjustable to various positions, serves to limit the movement of the pawl lever with the oscillating lever. The position of the stop member serves to determine the rate of feed as will be explained hereinafter. The pawl lever, through a pawl and ratchet mechanism and a friction clutch, effects intermittent rotative movement of a feed shaft. The feed shaft is connected to the feed screw through a gear mechanism which may be controlled to vary the direction of rotation of the feed screw and accordingly to vary the direction of the feeding movements of the table on the rail. The direction of the feeding movements effected by the table is controlled by a hand grasp having a stationary pivot on the rail and the rate of feeding is controlled by a hand grasp which may be operated when the machine is in operation.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:

Figure 1 is an elevational view of a shaper having a feed mechanism constructed in accordance with my invention. Fig. 2 is a sectional view along the line 2—2 of Fig. 1. Fig. 3 is a sectional view along the line 3—3 of Fig. 2. Fig. 4 is a sectional view along the line 4—4 of Fig. 2. Fig. 5 is a sectional view along the line 5—5 of Fig. 2. Fig. 6 is an isolated view of the oscillating lever looking in a direction opposite to Fig. 5. Fig. 7 is a detailed view of the stop member. Fig. 8 is a detail view of the oscillating lever, stop member and the pawl lever.

Referring to the accompanying drawings and particularly to Fig. 1, a shaper 1 is illus-

trated comprising a main frame 2, a reciprocating ram 3, and a work-carrying table 4. The ram 3 is reciprocated on suitable ways by means of a rocker arm 5 which is operated in a conventional manner by means of a crank gear wheel 6. A tool-head 7, which is mounted on the ram 3, carries a suitable cutting tool 8 for operating on the work carried by the table 4. The work-carrying table 4 is mounted on a cross rail 9 and is moved along the cross rail in a horizontal direction by means of a feed screw 10. The cross rail 9 is vertically movable on the main frame of the machine in a conventional manner.

Referring to Fig. 2 of the drawings, the crank wheel 6 is journaled in a hub 12 projecting from the main frame 2 of the machine. A plate 13, which is secured to the gear wheel 6 by bolts 14, one only of which is illustrated, carries a bevel-gear wheel 15 for operating the table feed mechanism. The bevel-gear wheel 15 is secured to the plate 13 by bolts 16, one only of which is shown in Fig. 2 of the drawings. A shaft 17, which controls the stroke of the ram 3 in a conventional and well-known manner, projects through the bevel-gear wheel 15 and the plate 13 and is provided with a bearing in a bracket or housing 2^a which is secured to the hub 12. A squared end 18 on the shaft 17 is adapted to be engaged by a crank handle for controlling the throw of the rocker arm 5, and accordingly the stroke of the ram 3. A bushing 19 on the shaft 17 and a hand-grasp 20 are provided for preventing longitudinal movement of the shaft.

The bevel-gear wheel 15, which is secured to the plate 13, meshes with a bevel-gear wheel 21 which is connected to a universal shaft 22. A hub portion 23 of the bevel gear wheel 21 is supported by a bushing 24 in the housing 2^a. A suitable washer or collar 25 is provided between the bevel-gear wheel 21 and the housing 2^a as shown in Fig. 2 of the drawings. The universal shaft 22 has one end thereof supported in a casing 26 on the cross rail 9, and is so constructed as to allow for the vertical movement of the cross-rail 9 with respect to the main frame 2. An end link 27 of the universal shaft 22 is supported in the casing 26 by means of a bushing 28 and a crank arm 29 is secured to the link 27 by means of a pin 30. The crank arm 29 is connected to an oscillating lever 31 by means of two pins 32 and 33 and a link 34. The pin 32 is fixedly secured to the crank arm 29 by means of a pin 35. A bushing 36 is provided for rotatively supporting the link 34 on the pin 32. The pin 33 is fixedly mounted in the oscillating lever 31 and permits free rotative movement of the link 34 thereon. The pin 33 not only connects the link 34 of the oscillating lever 31 but also provides a projecting or contact portion 38 for engaging a pawl lever 39. 130

The projecting portion 38 is provided with a suitable cushion 40, preferably constructed of leather, for engaging the pawl lever. The oscillating lever 31 is provided with a bearing in a wall 41 of the casing 26 and the pawl lever 39 is rotatively mounted on a feed shaft 42. The feed shaft 42 projects through the oscillating lever 31 for operating the feed screw 10 in a manner to be hereinafter set forth.

Referring particularly to Figs. 3, 5, 6 and 8, the operation of the pawl lever 39 by the oscillating lever 31 will be described. The oscillating lever 31, as above set forth, carries the pin 33, which has a leather cushion 40 for engaging the pawl lever 39. The leather cushion 40 engages a surface 44 on the pawl lever as best shown in Fig. 5 of the drawings. A spring member 45, which has one end connected to the pawl lever 39 and the other end thereof connected to a lug 46 on the casing 26, serves to exert a force tending to hold the pawl member 39 in engagement with the pin 33 on the oscillating lever 31. The oscillating lever 31 is oscillated through a fixed arc by reason of the continuous rotation of the crank arm 29. The crank arm 29, as above set forth, is continuously rotated by means of the universal shaft 2. Thus, if the pawl lever 39 is held in engagement with the oscillating lever 31 at all times by the spring member 45 such pawl lever will effect oscillations through the same arc as the oscillating lever 31. However, a stop member 46 is provided for limiting the movement of the pawl lever with the oscillating lever.

The stop member 46 is rotatably mounted on a hub portion 47 of the pawl lever 39 and worm teeth 48 are formed on the perimeter of the stop member 46, as shown in Figs. 3 and 8 of the drawings. The worm teeth 48 mesh with a worm 50 which is formed on an adjusted shaft 51. The shaft 51 and the worm 50 serve to adjust the position of the stop member 46 and accordingly to vary the rate of feeding effected by the work table 4. The shaft 51 is journaled in the casing 26, as shown in Figs. 4 and 5 of the drawings, and is held against longitudinal movement by means of a shoulder 52, which is formed on the shaft, and a collar 53 which is pinned to the shaft. A hand grasp 54 which is provided with a knurled end 55 is splined to the shaft 51 and serves as a means for adjusting the rate of table feed. A spring member 56, which surrounds the shaft 51 as shown in Fig. 4 of the drawings, is positioned between a shoulder 57 formed on the hand grasp 54 and a shoulder 58 which is formed on the shaft 51. Such spring 56 serves to exert a force tending to hold the hand grasp in engagement with the side of the casing 26. A pin 59, which is secured to the casing 26, is adapted to enter holes 60 which are formed

in a flange 61 of the hand grasp 54. The pin 59 cooperating with holes 60 serves to hold the feed adjusting mechanism in any set position. The holes 60 are positioned in the flange 61 to effect any predetermined rate of feed and a scale 62 is formed on the perimeter of the flange 61 to indicate the rate at which the feed will be effected.

The stop member 46 is provided with a projection 64 for engaging the pawl lever 39. The pawl lever 39 is provided with a surface 65 having a cushion of any suitable material, such for example as leather 66, for engaging the projection 64. The leather cushions 40 and 66 on the pin 33 and the pawl lever 39 are not absolutely essential but serve to insure more silent operation of the various levers and prevent the clicking noise which otherwise would be produced. The pawl lever 39 carries a pawl member 67 which is adapted to engage ratchet teeth 68 formed on the perimeter of a clutch member 69. The clutch teeth 68 form a well-known one-way ratchet so that the pawl member 67 only operatively engages the teeth in one direction of movement of the pawl lever 39. Thus, the clutch member 69 is only moved with the pawl lever 39 when the pawl lever is moved in a counter-clockwise direction as viewed in Figs. 4 or 5 of the drawings. A plunger 70, which is mounted in an orifice 71 formed in the pawl lever 39 is held in engagement with the end of the pawl 67 by means of a spring 72 to hold the pawl member in engagement with the ratchet teeth 68.

The clutch member 69 is rotatively mounted on the feed shaft 42 and is connected by friction means to a driven clutch member 76 which is keyed to the shaft 42. A plate 77 is held in engagement with a shoulder 78 on the feed shaft 42 by means of spring members 79 located in holes formed in the clutch member 69. The plate 77 is compelled to rotate with the clutch member 69 by means of a pin 80 which is best shown in Fig. 3 of the drawings. The spring members 79 engaging the plate 77 force the clutch member 69 into a cup-shaped orifice formed in the driven member 76 and into frictional engagement with a leather friction plate 82. The amount of friction produced between the driving and driven members controlled by means of the nut 83, which is threadably connected to the end of the shaft 42.

Briefly reviewing the operation of the parts so far described, which are mounted in the casing 26, it will be noted the lever 31 is continuously oscillated through a fixed arc by means of the constant rotation of the crank lever 29. The constant oscillation of the oscillating lever 31 effects an oscillatory movement of the pawl lever 39. The arc, through which the pawl lever 39 is oscillated, is determined in accordance with the position of the stop member 46. The stop

member may be so set as to permit the pawl lever to be held in engagement with the oscillating lever at all times. In such case the pawl lever would be oscillated through the same arc as the oscillating lever 31. Referring to Fig. 5 of the drawings the operation of the stop member 46 in controlling the arc through which the pawl lever 39 is vibrated will be described. In this description it will be assumed the crank-arm 29 is constantly rotated in a counter-clockwise direction as viewed in Fig. 5 of the drawings. The counter-clockwise rotation of the crank lever 29 will first cause a movement of the oscillating lever 31 in a counter-clockwise direction to engage the pawl lever 39 and move such pawl lever in a counter-clockwise direction against the tension of the spring 45. When the oscillating lever 31 reaches the extreme end of its counter-clockwise movement and starts its return movement in a clockwise direction, the spring member 45 holds the pawl lever 39 in engagement with it. However, the stop member 46 may be set by means of the hand grasp 54 in a position to stop the movement of the pawl member 39 before the oscillating lever 31 has reached its extreme travel in a clockwise direction. By such means the arc of oscillation of the pawl lever is varied with respect to the arc of oscillation of the oscillating lever 31. The gearing connection between the crank gear wheel and the universal shaft 22 is so adjusted that the oscillating lever 31 engages the pawl lever 39 during the return stroke of the ram 3. The amount of movement of the pawl lever 39 during the return stroke of the ram is determined in accordance with the position of the stop member 46. In very small feeds the pawl member 39 would only be engaged by the oscillating lever 31 at the extreme end of the return stroke of the ram.

The feed shaft 42 carries a bevel gear wheel 90 which meshes with two bevel gear wheels 91 and 92 on the feed screw 10. The bevel gear wheel 90 is fixedly mounted on the feed shaft 42 and the bevel gear wheels 91 and 92 are rotatively mounted on the feed screw 10. A clutch member 93 is splined to the feed screw 10, as shown in Fig. 2 of the drawings, and is provided with clutch teeth 94 and 95 which are respectively adapted to engage clutch teeth 96 and 97 on the bevel gear wheels 91 and 92. Thus, the clutch member 93 may be moved into engagement with the teeth 96 on the bevel gear wheel 91 for rotating the feed screw 10 in one direction and may be moved into engagement with the clutch teeth 97 on the bevel gear wheel 92 for rotating the feed screw in an opposite direction. The clutch member 93 is shifted on the feed screw 10 by means of a shaft 99. An eccentric pin 100, secured to one end of the shaft 99, is

fitted to a groove 101 formed in the clutch member 93. The shaft 99 is provided with a bearing in the casing 26 and is rotated by means of a handle or hand grasp 102. A spring pressed ball 103 is mounted in an opening formed in the casing 26, as shown in Fig. 3 of the drawings and engages notches 104 formed in the shaft 99 for holding the clutch member 93 in a neutral or an operative position.

Reviewing the operation of the feed mechanism it will be noted continuous rotative movement is supplied from the crank gear wheel 6 to the feed mechanism in the casing 26 by means of the universal shaft 22. Such shaft 22 is rotated directly in accordance with the movement of the reciprocating ram 3. The universal shaft 22 through the crank 29 oscillates the lever 31 through a fixed arc. The oscillating lever 31 oscillates the pawl lever 39 through an arc which is varied according to the position of the stop member 46. The stop member 46, which is controlled by the hand grasp 54, serves to determine the rate of feeding by the work table. The pawl lever 39 by means of the pawl member 67 and the clutch mechanism comprising the driving and driven members 69 and 76 effects intermittent movement of the feed shaft 42. The feed shaft 42 is connected to the feed screw 10 through the bevel gear wheels 90, 91 and 92 for operating the feed screw 10 according to the position of the clutch member 93. Thus, the rate of feed effected by the feed screw 10 is controlled by the hand grasp 54 and the direction of feed effected by the feed screw 10 is controlled by the handle 102. Both the hand grasp 54 and the handle 102 are mounted on the cross rail 9.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims:

Having thus revealed this invention, I claim as new and desire to secure the following combinations and elements, or equivalents thereof, by Letters Patent of the United States:

1. A shaper feed mechanism comprising a crank-gear wheel; feed means comprising a shaft rotating once for each stroke of the shaper ram and having one end geared to said crank-gear wheel and the other end thereof supported on the shaper cross rail; a lever on the cross rail; means operated by said rotating shaft for oscillating said lever

- through a fixed arc; a pawl lever mounted on the cross rail and oscillated by said oscillating lever; means mounted on the cross rail for varying the arc through which said pawl lever is oscillated; a feed screw 5 for moving the shaper table along the cross rail; a ratchet-wheel for intermittently rotating said feed screw in accordance with the movement of the pawl lever; and a bevel-gear reverser between said feed-screw and said ratchet wheel. 10
2. A feed mechanism for a shaper having a cross-rail; a ram reciprocated by a rotating crank gear wheel, feed means connected thereto and comprising a shaft extending to said cross-rail and continuously rotated in accordance with the rotation of the crank gear wheel; a lever mounted on said cross-rail; means operated by said shaft for oscillating said lever through a fixed arc; a pawl-lever oscillated by said oscillating lever; means for varying the arc through which said pawl lever is oscillated; a feed screw; a pawl and ratchet-wheel for operating the feed screw in accordance with the movement of the pawl lever; and a motion reverser 25 between said ratchet-wheel and said feed-screw. 30
3. A shaper feed mechanism comprising a crank-gear wheel; continuously rotating shaft having one end thereof geared thereto and having its other end supported on the shaper cross rail; an oscillating lever mounted on the shaper cross rail; a crank mechanism operated by the rotating shaft for oscillating said lever through a fixed arc; a pawl lever mounted on the cross rail and oscillated invariably to the same forward position by means of said oscillating lever; a stop member for limiting the arm through which the pawl member may return; a feed screw for feeding the shaper table along the cross rail; and means for operating the feed screw in accordance with the movement of the pawl lever. 45
4. A feed mechanism for a shaper having a ram operated by a crank gear wheel and comprising a shaft continuously rotated by said gear wheel once for each stroke of the ram; a lever; a cross-rail carrying said lever; means operated by the rotating shaft for positively oscillating said lever to and fro through a definite arc; a pawl lever moved positively by the oscillating lever during the return stroke of the ram; a spring for causing said pawl-lever to return with said other lever; a stop mounted coaxially with said pawl-lever for limiting the return-movement of the pawl lever; a stationary hand-grasp for shifting said stop about its axis; a feed screw for moving the shaper table along the cross rail; and means comprising a constantly engaged pawl and ratchet-wheel for operating said feed screw 55
- by the pawl lever during the latter part of the ram return stroke. 5
5. A feed mechanism for a shaper having a cross-rail; a ram operated by a crank gear wheel; feed means driven by said wheel and comprising a shaft extending to said cross-rail and continuously rotated in unison with said gear wheel; a lever mounted on the shaper cross rail; means operated by the rotating shaft for oscillating the lever through a definite arc; a pawl lever advanced always to the same foremost station by the oscillating lever during the return stroke of the ram; a spring for keeping said levers in contact during the first portion of the return-stroke of said lever; a feed screw for moving the shaper table along the cross rail; and means for operating said feed screw by the pawl lever during the latter part of the ram return stroke. 70
6. A shaper feed mechanism comprising a ram; a crank-gear wheel; a cross-rail; a rotating shaft driven by said wheel and having one end thereof supported on the cross rail; a lever on said cross-rail oscillated through a fixed arc by said rotating shaft, a pawl lever rotatably mounted concentric with said oscillating lever and having a portion thereof in the path of movement of a projection from the oscillating lever; resilient means for exerting a force tending to hold said pawl lever in engagement with said oscillating lever; an adjustable stop member for limiting the period of contact between the pawl lever and the oscillating lever during its return stroke; and a feed shaft intermittently operated by said pawl lever. 80
7. A shaper feed mechanism comprising a crank-gear wheel; feed means geared thereto and including an uni-directional rotating shaft having one end thereof supported on the cross rail; a lever mounted on the cross rail; means operated by said shaft for oscillating the lever through a fixed arc; a pin projecting from the side of the lever; a rotatable pawl lever mounted concentric with said oscillating lever and having a portion thereof in the path of movement of said pin; an adjustable stop member also mounted concentric with said oscillating lever for limiting the movement of the pawl lever in one direction; a resilient member for exerting a force tending to hold the pawl lever in engagement with the stop member; a feed screw; and means for operating said feed screw in accordance with the movement of the pawl lever by the oscillating lever. 90
8. A shaper mechanism comprising a reciprocating ram; mechanism including a rotating crank gear wheel for reciprocating said ram; a cross rail; a work table mounted on the cross rail below the reciprocating ram; a feed screw mounted on the cross 100
- 105
- 110
- 115
- 120
- 125
- 130

- rail and connected to said table; a universal shaft rotated in a uniform direction by said crank gear wheel; a feed shaft mounted on the cross rail and adapted to be connected to said feed screw; a lever mounted concentric with said feed shaft and oscillated through a given arc by means of said universal shaft; a pawl lever rotatably mounted on said feed shaft and oscillated through various arcs by means of said lever; a stop 5 rotatably mounted on said pawl lever for controlling the oscillating movement of the pawl lever; resilient means for exerting a force tending to hold the pawl lever in engagement with the stop and in position to be engaged by the oscillating lever; a worm and worm-wheel for shifting said stop; and means controlled by said pawl lever for operating the feed shaft to effect feeding movement by the feed screw.
- 10 9. A shaper feed mechanism comprising a shaft continuously rotated in one direction once for each stroke of the shaper ram; means for converting said rotary movement of the shaft into oscillatory movement at a point on the cross rail; stationary means comprising a worm on the cross rail for varying the arc of said oscillatory movements to vary the feeding rate; and means 15 controlled by said oscillatory movements for operating the feed shaft to effect feeding movement by the feed screw.
- 20 9. A shaper feed mechanism comprising a shaft continuously rotated in one direction once for each stroke of the shaper ram; means for converting said rotary movement of the shaft into oscillatory movement at a point on the cross rail; stationary means comprising a worm on the cross rail for varying the arc of said oscillatory movements to vary the feeding rate; and means 25 controlled by said oscillatory movements for operating the feed shaft to effect feeding movement by the feed screw.
- 25 9. A shaper feed mechanism comprising a shaft continuously rotated in one direction once for each stroke of the shaper ram; means for converting said rotary movement of the shaft into oscillatory movement at a point on the cross rail; stationary means comprising a worm on the cross rail for varying the arc of said oscillatory movements to vary the feeding rate; and means 30 controlled by said oscillatory movements for operating the feed shaft to effect feeding movement by the feed screw.

In witness whereof, I have hereunto subscribed my name.

WILLIAM F. ZIMMERMANN.
